UNITED STATES PATENT OFFICE.

PERCY E. BARKER, OF CLEVELAND, OHIO, ASSIGNOR TO THE VAN DORN IRON WORKS COMPANY, OF CLEVELAND, OHIO, A CORPORATION OF OHIO.

DUMP TRUCK.

Application filed August 27, 1921. Serial No. 496,115.

This invention relates to improvements in hoist or dump trucks.

The objects of this invention are to provide means for preventing raising or lowering movement of the truck body while the gears are in reverse drive; to provide means for preventing the accidental settling of the truck body by gravity while the truck itself is in motion; to provide a swivel connection 10 between the cross head and its operating mechanism so as to prevent the shock from a blow to the cross head being transmitted to the operating mechanism of the cross head; to provide an improved means for 15 automatically limiting the raising and lowering movements of the truck body; and to provide an automatic oiling means.

Other objects of this invention will appear from the following description and 20 claims when considered together with the accompanying drawings.

Fig. 1 is a side elevation of my truck; Fig. 2 is a detail elevation of the drive connection to the hoisting mechanism; Fig. 3 is a detail view of the one-way clutch to the 25 hoisting mechanism; Fig. 4 is a detail view of the hoisting mechanism; Fig. 5 is a detail view of the latch for the lever rod for controlling the hoisting mechanism; Fig. 6 is a section taken on line 6—6 of Fig. 4; Fig. 7 is a section taken on line 7—7 of Fig. 4; Fig. 8 is a detail view of the oil valve; Fig. 9 is a section on line 9—9 of Fig. 4; Fig. 10 is a side view of the dog engaging the notch; Fig. 11 is an inverted plan view of the notch 30 engaged by the dog; Fig. 12 is a detail view of a trip button on the hoisting nut; and Fig. 13 is an elevation of the hoisting mechanism.

In the device as here shown gas engine 1 as usual is mounted on the front end of the chassis 2 and has drive connection through the gearing enclosed in the casing 3 with the shaft 4 and the aligned shaft 4' which extends rearwardly to the rear axle. The gearing enclosed in the casing 3 includes the combination for high, low and intermediate speeds as well as for reverse drive. The truck body 5 which is pivotally mounted at 45 6 at the rear end of the chassis is adapted to be raised and lowered by means of the cables 7 attached at 8 to the depending arms 9 on the front end of the truck body and attached at their other ends to the chassis at

the points 10. The hoisting movement is effected by means of the sheaves 11 which are suitably supported for rectilinear motion in an upward direction by means of mechanism operated from shaft 4, as will be later described.

The transmission casing 12 encloses a clutch member 13 which is keyed upon shaft 4 and is adapted upon actuation of the operating shaft 14, connected to yoke 14' to be thrown into engagement with the companion clutch member 15 fast upon the drive shaft 4' for driving operation of the truck. The clutch member 13 can also be shifted forwardly for engagement with the companion clutch member 16 which is loosely mounted upon the shaft 4 and which carries a sprocket 17. This sprocket by means of the chain 18 has driving connection with the smaller sprocket 19 which is loosely mounted upon and has one way clutch connection with the shaft 20. This one way clutch connection comprises the inclined and toothed surface of the sprocket member 19 for driving connection with the correspondingly formed surface on the companion clutch member 21 which is slidably mounted upon the shaft 20. An annular shoulder 22 is provided upon one end of the clutch member 21 and forms an abutment for one end of the spiral spring 23 which abuts at its other end 35 against the annular ring 24. The ring 24 is forced by the spring 23 against the pin 25 which extends through the end portion of the shaft 20 and also through the diametrically disposed slots 26 provided in the ends 40 of the clutch member 21. Thus a positive drive is effective from the sprocket 19 through the engaging teeth of the two clutch members, from the clutch member 21 through the pin 25 to the shaft 20. This 45 drive connection is effected when the sprocket 19 is operated in one direction only, that is, when the engine is set for direct or forward drive. When, however, the gears are shifted for reverse drive of the truck, the inclined or cam faces of the clutch member carried by the sprocket 19 will slip past the cam faces of the clutch member 21 and cause a movement of the clutch member 21 along the shaft 20 against the tension of the 50 spring 23, which straight line movement is permitted by the slot and pin arrangement at the outer ends of the shaft and clutch.

member 21. Thus when the truck is in reverse drive, no motion will be transmitted through the clutch to the shaft 20. Other forms of one-way clutches may be used at this point.

The sprocket 19 and the chain 18 are enclosed in the casing 30 which is bolted upon the top of the transmission casing 12. The shaft 20, as it extends to the right of the sprocket 19, as viewed in Fig. 3, is given suitable support in the tubular bearing 31 which is attached by means of the bolts 32 to the side of the cast metal base 33 of the casing 34 which encloses the nut and screw mechanism for raising and lowering the truck body. A bushing 34^a is provided and the shaft 20 is given positive driving connection with the stub shaft 34' by means of the screw threaded connection 35 and the lock pin 36. The bushing 37 is also provided and a space 38 is preserved at this point between the bearing 31 and the shaft 20. With this arrangement I am enabled to attach my hoisting mechanism including the one-way clutch connection to a standard mechanism for raising and lowering the truck body. In this particular instance the only parts necessary for such drive connection are the tubular supporting member with its bushings and the connection just now described between the shaft 20 and the stub shaft 34'.

The cast metal base 33 is supported upon the chassis in any suitable manner as for instance by the screw bolts 40 and is engaged by the brace rods 41 which engage at their upper ends ears provided upon the cast metal top portion 43. The casing 34 is secured within the cast metal base by means of the bolts 41' and is secured by means of the bolts 42 at its upper end to the cast metal top portion 43 which is formed at one side with a housing 44 for enclosing the connection between the operating handle 45 and the upwardly extending operating rod 46. As seen in the drawings, the base and casing are inclined slightly to the rear. The handle 45 is fast upon the shaft 47 which is mounted in the top portion 43. A yoke member 50 is also rigidly mounted upon the shaft 47 by means of set screw 51 extending through the shoulder of the yoke member 50 and engaging the shaft 47. The oppositely disposed arm of the yoke member 50 terminates at points on diametrically opposed sides of the screw shaft 54, while the rearwardly extending portion 55 of the yoke member terminates in a ball shaped portion which is adapted for swivel connection in the socket 56 of the upwardly extending rod 46. A clevis 60, screw threaded on rod 46 has pivotal connection with the rod 61 which extends through the tubular guide portion 62 formed on the cast metal base 33. The lower end of the rod 61 is connected at 63 with the yoke 64 which is adapted for operative en-

gagement with the annular groove 65^a of the intermediate clutch member 65. This clutch member 65 is keyed, as indicated at 65^b upon the lower plain end portion of the screw shaft 54 and is adapted for drive connection with either the upper or lower bevel gears 66 and 67, respectively which are freely mounted with the intermediate bushings upon the screw shaft 54. These bevel gears are suitably mounted by means of screw bolts upon the annular flanges 66^a of hubs 66^b which surround the screw shaft with intermediate bushings and are supported in such position by means of the thrust collars 66^c and 66^d. The stub shaft 34' has fixedly mounted upon its other end the intermediate bevel pinion 80 which meshes with both the upper and lower bevel gears 66 and 67. Thus it will be seen that upon operation of the shaft 34' both of the bevel gears 66 and 67 will be operated in opposite directions, but no motion of the screw shaft 54 will be caused unless the clutch member is moved upwardly or downwardly into clutched engagement with gear 66 or 67.

The present structure is so arranged that upon movement of the handle 45 to the right, as viewed in the drawings, the operating rod 46 will be moved upwardly which means that the intermediate clutch member will be brought into driving connection with the upper bevel gear 66. The screw shaft is then operated for upward movement of the truck body by means of the nut 90 which will be caused to move upwardly along the screw shaft. The nut 90 is prevented from rotating by means of the key 91 secured in any suitable manner as by riveting along the inner face of the casing 34. Rigidly mounted upon the nut 90 by means of the pin and slot connection 93 is the plunger 94 which at its upper end has swivelling connection with the cast metal support 95 for cross head 96 carrying the sheaves 11. The connection at 93 is a rigid one by virtue of the fact that the companion semi-circular grooves in the nut and plunger extend only tangentially and thus prevent any relative movement between these two parts. Whereas, the pin and slot connection between the upper member 95 and the plunger 94 allows a swivelling movement between these two parts because of the fact that the groove in the cast member extends completely thereabout with a straight pin engaging tangentially in only a portion of the groove. Thus the force of a blow striking the cross head will not be transmitted to the mechanism at the lower end of the plunger.

The upper cast member 95 is provided at its extreme upper portion with an oil reservoir 100 closed by a suitable screw cap 101, this oil chamber having extending therethrough a tubular portion 102 through which extends the supporting pin 103 for the cross

head 96. Cotter pins 104 maintain the cross pin in proper position. The lower portion of the cast metal member 95 is provided with the annular inwardly extending web 106, which defines the bottom of the oil reservoir 100. This web has seated therein by means of screw threaded engagement the valve casing 107 within which is mounted the valve stem 108 carrying at its upper end the valve 109 and at its lower end the valve 110. Conical seats are provided for these two valves and a spring 111 normally holds the lower valve 110 in open position with the upper valve closed. The spring 111 which abuts at its lower end against the valve 110 has bearing engagement at its upper end against the web 112 fixed within the valve casing and extending as a guiding portion 113 for the pin 108 and terminating in the web 114. A pin 120 is seated within the upper end portion of the screw shaft and is normally forced upwardly by means of the spiral spring 121 which has suitable abutment at 122 at its lower end. A suitable stop is provided at 125' for the shoulder 126' formed upon the pin 120 so as to limit its upward movement. Thus it will be seen that when the cross head and likewise the truck body are in extreme lowered position, the valve 110 will strike the pin 120; and since the spring 121 is stronger than the spring 111, the valve 110 will be closed and the valve 109 opened. The valve casing 107, which serves as an oil measuring and delivering device, is now filled up by oil flowing from the chamber 100 through the ports 125 and 126 provided in the webs 112 and 114, respectively. Then upon raising the truck body by upward movement of the cross head, the valve 110 will leave the rod 120 and the tension of spring 111 will cause the valve 109 to close and the valve 110 to open. The oil contained within the casing 107 is then permitted to flow by gravity out of the valve casing down through the plunger 94 past the guide sleeve 130 and to the top of the nut 90 which is provided with ports 132 for passage of the oil therethrough. These ports communicate at their lower ends with the chamber 133 within which are enclosed wicks 134 extending out through the side of the plunger 90. The oil which will work its way by capillary attraction up through the wicks will pass outside of the plunger 94 and on to the lower portion of the nut which it then passes and finally reaches the gearing in the lower portion of the casing. The oil eventually settles in the base cover 140 which is removably secured to the cast metal base by means of the bolts 141.

The extreme lower end of the cast metal base encloses also the thrust bearings 142 and 143 for the lower end of the screw shaft. As will be apparent, the thrust collar 142 will take up longitudinal or vertical thrust

while the lower thrust collar will take up transverse thrust upon this end of the screw shaft. The thrust collar 142 is keyed as indicated at 145 to the screw shaft and a set screw 146 secures the lower thrust collar 143 in locked position after being screw threaded upon the extreme lower end of the shaft as indicated at 147. Suitable washers 148 and ball bearings 149 are provided for the thrust collars. The upper thrust collar 142 is provided with a notch 150 formed in the upper face of this collar. The notch 150 is adapted for engagement by the dog 155 which is pivotally mounted by means of a pin upon the flanged strap 156 which in turn is secured by means of bolts to the lower portion of the bevel gear 67. A cotter pin 170 secures the pin which extends through the registering apertures in the depending flanges 155' of the strap and the dog. The object of this dog and notch construction is to prevent accidental settling of the truck body by gravity while the truck is in motion. As will be seen from the drawings, any tendency of the nut 90 to work its way downwardly and to thereby cause a turning movement of the screw shaft will cause the dog 150 to engage the wall at the end of the notch and to prevent what would otherwise result in the turning of the screw and lowering of the truck body. Such a locking of the parts against such movement is made possible in my device because of the fact that the mechanical driving connection between the thrust collar 142 on the screw 54 through the bevel gears, shafts 34' and 20 to the sprocket wheels 19 and 17 constitutes sufficient load to prevent turning of the screw shaft. Relative movement in the opposite direction is permitted between collar 142 and gear 67 since the pivoted dog will ride up the inclined face 150a of the notch and thus pass over the same.

The tubular portion 62 of the cast metal base 33 is provided with an outwardly extending boss 185 within which is screw threaded a housing 186. A latch pin 187, provided with a transverse stop pin 188 in its outer end, extends through this housing and is surrounded by a spiral spring 188' abutting against the shoulder of the tapered end portion 189 of the pin and normally forces the same into engagement with one of the recesses 190 in the operating rod 61. The purpose of this structure is to automatically hold the operating rod 46 in the position to which it is brought, there being provided three notches corresponding to the raising, lowering, and neutral positions of the intermediate clutch member 65. As a means of automatically limiting the raising and lowering movements of the cross head I have provided a trip button 191 mounted in a boss upon the side of the base portion of the nut 90, this trip member being adapt-

ed for engagement with the lower face of the yoke member 50 which, as will be apparent, extends downwardly while the operating handle 145 is set for raising operation of the truck body. Then when the operating handle 45 is set for lowering operation of the truck body, the yoke arm will extend somewhat upwardly and with my mechanism will be engaged by the downwardly extending pins 192 which are suitably mounted upon the cross head at 192^a and extend through guides 192^b on the cast member 43 to the inside of the same.

From the above it will be seen that with my device I am able to either raise or lower the truck body with the gears set for high, low or intermediate speed, but such operation is possible only during direct drive of the truck because of the one way clutch connection which makes it impossible to transmit motion from the motor to the nut and screw mechanism during reverse drive. It will also be clear that the truck itself can be propelled forwardly or backwardly only when the hoisting mechanism is disconnected from the drive shaft of the motor, due to the control by the sliding clutch member 13 of the connection of the motor either to the vehicle wheels or to the hoisting mechanism.

Prevention of drive to the body raising and lowering mechanism during reverse drive of the shaft 4 is important to positively prevent injury to the mechanism by incorrect manipulation of the control devices by the operator. Assuming that a drive connection is established to shaft 20 the operator initiates body raising movement by actuation of the operating handle 45. When the raising movement is completed the clutch 65 is automatically thrown out by the mechanism, and the operator is then able to move said clutch in the same direction into engagement with the opposite driving clutch member. However, if in the meantime the operator has shifted the gears in the transmission mechanism to rotate shaft 20 in the reverse direction, closing of the clutch by the operator would not lower the body but would so connect the parts as to again raise the nut and plunger, forcing the parts out through the top of the column. The mechanism described absolutely prohibits such improper manipulation.

Several of the advantages flowing from this invention may be summarized as follows. First, with my mechanism in which it is impossible to raise or lower the truck body while the truck is in reverse drive connection, I avoid the danger of unloading the truck in the path of movement of the truck itself. It is also impossible with my device for the truck body to accidentally settle into lower position during movement

of the truck whereby the truck body can be maintained at the elevation desired while moving the truck forwardly. The swiveling connection between the cross head and the plunger prevents the shock of an outside blow from being transmitted to the mechanism which means that the life of the mechanism will be prolonged. My automatic means for oiling the hoisting mechanism and the improved means for automatically limiting the raising and lowering movements of the truck body mean prolonged life for the mechanism as well as an increased efficiency.

Other objects resulting from this invention will be apparent to those who are familiar with the art to which it relates.

Having described my invention, I claim:

1. In a motor truck, the combination of a chassis, a truck body mounted upon said chassis and capable of raising and lowering movement, reversible rotating means for propelling said chassis, body raising and lowering means of a form requiring driving rotation in one direction only to effect the raising and lowering of the truck body, and power transmitting means connecting said raising and lowering means for operation by said reversible propelling means and including means for transmitting but a single direction of rotation.

2. In a motor truck, the combination of a chassis, a truck body mounted upon said chassis and capable of raising and lowering movement, reversible rotating means for propelling said chassis, body raising and lowering means including reversing mechanism and having a part requiring driving rotation in one direction only to effect the raising and lowering of the truck body, and power transmitting means connecting said raising and lowering means for operation by said reversible propelling means and including means for transmitting but a single direction of rotation.

3. In a motor truck, the combination of a chassis, a truck body mounted upon said chassis and capable of raising and lowering movement, reversible rotating means for propelling said chassis, body raising and lowering means including a screw shaft and a clutch and having a part requiring driving rotation in one direction only to effect the raising and lowering of the truck body, limit devices for automatically controlling said clutch, and power transmitting means connecting said raising and lowering means for operation by said reversible propelling means and including means for transmitting but a single direction of rotation.

4. In a motor truck, the combination of a chassis, a truck body mounted upon said chassis and capable of raising and lowering movement, means for propelling said chassis and lowering and raising said body, and

means for preventing accidental lowering of said body, said means including automatic locking mechanism cooperating with said raising and lowering means.

5. In a motor truck, the combination of a chassis, a truck body mounted upon said chassis and capable of raising and lowering movement, means for propelling said chassis and lowering and raising said body, and 10 means for preventing accidental lowering of said body, said means including automatic locking mechanism located in the train of said raising and lowering means.

6. In a motor truck, the combination of 15 a chassis, a truck body mounted upon said chassis and capable of raising and lowering movement, mechanism for propelling said chassis, mechanism for raising and lowering said body, means for operating said mechanisms, and oiling means for said raising and lowering mechanism, said oiling means being automatically controlled by the operation of said raising and lowering mechanism.

25 7. In a motor truck, the combination of a chassis, a truck body mounted upon said chassis and capable of raising and lowering movement, mechanism for propelling said chassis, mechanism for raising and lowering said body, means for operating said mechanisms, and means for intermittently oiling said raising and lowering mechanism, said oiling means being controlled by the operation of said raising and lowering mechanism.

30 8. In a motor truck, the combination of a chassis, a truck body mounted upon said chassis and capable of raising and lowering movement, mechanism for propelling said 40 chassis, mechanism including a plunger for raising and lowering said body, means for oiling said raising and lowering mechanism, said oiling means being controlled by move-

ment of said plunger, and means for operating said mechanisms.

9. In a motor truck, the combination of a chassis, a truck body mounted upon said chassis and capable of raising and lowering movement, mechanism for propelling said chassis, mechanism including a plunger for raising and lowering said body, an oil reservoir carried by said plunger, a valve controlling the flow of oil from said reservoir to said raising and lowering mechanism, said valve being automatically controlled by 50 the operation of said raising and lowering mechanism, and means for operating said mechanisms.

10. In a motor truck, the combination of a chassis, a truck body mounted upon said chassis and capable of raising and lowering movement, mechanism for propelling said chassis, a plunger for raising and lowering said body, nut and screw mechanism for operating said plunger, an oil reservoir carried by said plunger, a valve controlling the flow of oil from said reservoir to said nut and screw mechanism, said valve being automatically controlled by the relative movement between said nut and screw, and means 65 for operating said mechanism.

11. In a motor truck, the combination of a chassis, a truck body mounted upon said chassis and capable of raising and lowering movement, mechanism for propelling said chassis, mechanism including a plunger for raising and lowering said body, an oil reservoir, means for measuring a predetermined quantity of oil to said raising and lowering mechanism, said measuring means 75 being controlled by movement of said plunger, and means for operating said mechanisms.

In testimony whereof I hereby affix my signature.

PERCY E. BARKER.
